Des. 240,518
Patented July 13, 1976

240,518

BABY WALKER

Hajime Ishida, 9-10 Tateishi 7-chome
Katsushika-ku, Tokyo, Japan

Filed July 7, 1975, Ser. No. 593,239

Term of patent 14 years

Int. Cl. D12—12

U.S. Cl. D12—130

FIG. 1

FIG. 2

FIG. 3

FIG. 4

FIG. 5

FIG. 6

FIG. 1 is a perspective view of my new baby walker;

FIG. 2 is a front elevational view thereof;

FIG. 3 is a rear elevational view thereof;

FIG. 4 is a left side elevational view thereof;

FIG. 5 is a top plan view thereof; and

FIG. 6 is a bottom plan view thereof.

The right side of the baby walker is substantially a mirror image of the left side shown in FIG. 4.

I claim:

The ornamental design for a baby walker, as shown and described.
